UNITED STATES PATENT OFFICE.

MICHAEL DUBICK, OF CHICAGO, ILLINOIS, ASSIGNOR TO EMPIRE MATTRESS COMPANY, OF CHICAGO, ILLINOIS, A CORPORATION OF ILLINOIS.

ROLL-EDGE STITCHER.

Application filed May 16, 1925. Serial No. 30,812.

This invention relates to the mattress making art, and more especially to sewing machines for stitching the so-called roll edge part of the mattress. The usual method of stitching these edges is to place the mattress on a table corresponding substantially in size with the mattress, and then running a sewing machine around the edge of the table on a suitable track, as is well understood by those acquainted with the art and skilled in mattress making, said machine being power operated, as by means of an electric motor. For the purpose of this invention, which is confined merely to a detail of the mattress feed and stitching mechanism proper, it is deemed sufficient to show merely that part of the machine which is immediately concerned, and which directly involves the improvement here claimed. In the machines heretofore used, the mattress holding and feed mechanism includes a pair of pointed fingers, both of which are tiltably mounted and are operative to coact with each other and engage the mattress edge for holding it while the stitch is being made. The operation, however, of this form of mechanism is not altogether satisfactory for the reason that the sharp pointed fingers enter the fabric and leave permanent marks thereon, and sometimes tear the fabric.

The main objects of the present invention are to provide an improved form of mattress holding and feed mechanism, adapted to avoid tearing or permanently marking the fabric of the goods, and more especially to provide a fabric engaging member adapted to bear against the upper side of the roll edge in a form and manner to effect a clamping contact, as distinct from a perforating grip on the goods. A further object is to provide either or both of the roll holding fingers with blunt faces to grip the fabric.

An illustrative embodiment of this invention is shown by the accompanying drawings, in which:

Figure 1 is a front elevation of that part of the device to which this invention applies.

Fig. 2 is a greatly enlarged fragmentary detail of the gripping mechanism and needle.

Fig. 3 is a front elevation or face view of the upper clamp member showing the broad, roughened friction face.

Fig. 4 is a front elevation, on a much reduced scale, of that part of the machine which embodies this invention, in its relation to the mattress and table which are here shown in vertical cross section. 60

Figs. 5 and 6 show modifications in the details of the roll holding finger tips.

The device herein shown and claimed is applicable to machines substantially similar in general character to those shown by certain patents issued to Joseph W. Droll, for example, Numbers 1,503,351, 1,511,403 and 1,519,299, of 1924, and Reissue No. 15,373, of 1922, and the present invention may be regarded as an improvement over the mattress stitching means shown by said patents. 65

In the construction shown in the drawings, the machine includes a sewing head 1, (see Fig. 4) including a pair of fabric engaging fingers 2 and 3, arranged to engage the outer and inner (upper and lower) sides respectively of the roll edge 4 of the mattress 5. These fingers 2 and 3 are tiltably mounted on medial pivots 6 carried by a pair of movable arms 7 in mutually spaced relation to admit the roll edge 4 when said fingers are swung apart. The outer ends of said fingers are pivotally connected at 8 to operating arms 9, which are actuated in the usual manner of such machines, as will be understood by those acquainted with the art. 75 80 85

Referring to the upper finger 2, it is to be noted that its fabric gripping part 10, instead of being pointed, is not only blunt but rather broad and flattish in character, with a roughened face adapted to prevent slippage of the material when forced into contact therewith by means of the opposite finger 3, which pushes the fabric up from the under side and holds it while the needle 11 shown in Fig. 2 is operated. Referring to Figs. 2 and 3, where this friction grip finger 2 is shown on a large scale, it is to be noted that the broad, flat bearing part 10, which engages the roll edge 5, lies in a plane at right angles to the general plane of said finger. The active face of this part 10 is corrugated by horizontal ridges 10' extending crosswise of the finger. Part of these ridges are notched at 10'' in alignment to accommodate the tip of the opposite finger 3 when the mattress is gripped. 90 95 100 105

The arms 7 are pivoted at their upper ex- 110

tremities at a point 12 which is movable up and down. The arms 9 are fastened in a suitable manner at their upper extremities to a common support with the pivot 12. In 5 operation, both arms 7 and 9 are moved downwardly together until a certain position is reached where the arms 7 come to a rest while arms 9 continue their downward movement, causing the active inner ends of 10 the fingers 2 and 3 to move inwardly on the fulcrums 6 and engage the roll edge 4, holding it in position for the needle to penetrate the same and draw in the thread 11 in making a stitch. When the pivot point 12 comes 15 to rest, the arms 9 are allowed to move downwardly against the tension of the springs 13.

When said head moves forward it must be raised clear of the mattress. The first downward movement just positions the sewing head 1 with relation to the mattress. The second downward movement causes the fingers to grip the mattress.

The face plate 14 of Fig. 4, which is 25 omitted in Fig. 1 and is indicated by dotted lines in Fig. 2, is notched at 15 to receive the roll edge 5.

In Fig. 5 the holding fingers 16 and 17 are 30 substantially alike and each has a blunt, flat, or somewhat rounded gripping face, 18,

as distinct from a point, and these faces which may be roughened in any effective manner when so required are here shown substantially plain. In Fig. 6 a knurled form of finger face 19 is shown.

35

Although but one specific embodiment of this invention is herein shown and described, it is to be understood that numerous details of the construction shown may be altered or omitted without departing from the spirit 40 of the invention as defined by the following claims.

I claim:—

1. In a stitching machine of the class described, two oppositely disposed pivotally mounted fingers, means for advancing and rotating the fingers to move the ends inwardly, the end of one of said fingers having a flat surface for opposing the end of the opposite finger.

2. In a stitching machine of the class described, two oppositely disposed pivotally mounted fingers, means for advancing and rotating the fingers to move the ends inwardly, one of said fingers having a blunt 55 flattened end having a roughened surface.

Signed at Chicago this 6th day of May 1925.

MICHAEL DUBICK.
